UNITED STATES PATENT OFFICE.

KENNETH E. STUART, OF PHILADELPHIA, PENNSYLVANIA.

SYSTEM OF ELECTRIC DESPATCH.

1,150,902.

Specification of Letters Patent. Patented Aug. 24, 1915.

Application filed September 9, 1910. Serial No. 581,208.

To all whom it may concern:

Be it known that I, KENNETH E. STUART, a citizen of the United States, residing at Philadelphia, in the county of Philadelphia and State of Pennsylvania, have invented a new and useful System of Electric Despatch, of which the following is a specification.

My invention relates to an electric system suitable for the despatch of mail, parcels, etc., and for other purposes, in which the traveling car carries no motorman; and my invention relates more especially to the system of control of the car.

My invention resides also in the system of car control wherein there is preferably employed a shunt wound direct current motor, the field of the motor being separately excited, and preferably at full voltage, to facilitate the control of the car, as during positive and negative acceleration, reversal, etc.

My invention resides in other features hereinafter described and claimed.

For an illustration of one of the forms my invention may take, reference is to be had to the accompanying drawings, in which:

Figure 1 is a view, in side elevation, some parts in section, showing the collector shoes and rotary switch. Fig. 2 is an end elevational view of the same. Fig. 3 is an end elevation of the rotary switch. Fig. 4 is a longitudinal sectional view of the rotary switch showing details of construction. Fig. 5 is an end elevational view, parts in section, of the rotary switch with the rotating parts omitted. Fig. 6 is a plan view, some parts in section, of the rotary switch. Fig. 7 is a diagrammatic view of the electric connections within the car when it is running at full speed. Fig. 8 is a diagrammatic view of the electrical connections within the car and between it and the controller when the car is at or near a station. Fig. 9 is a similar diagrammatic view showing the electrical connections for bringing the car to rest. Fig. 10 is a similar diagrammatic view showing the electrical connections when the car is reversed. Fig. 11 is a diagram showing the electrical connections between the track and controllers and generators at such a station.

The motor M, shown diagrammatically in Figs. 7, *et seq.*, is mounted upon the car and drives the wheels W through the pinion G meshing with the gear G¹ upon the driving axle A, the wheels W running upon the track rails, R², one or both of which may be

electrically connected to one terminal of the source of energy.

C represents a portion of the frame of the car to which electrical connection is made whereby electrical communication is afforded through the journal J and thence through the axles and wheels to the rail or rails R³.

The current is supplied to the motor by means of an insulated conductor rail T, through the collector shoe C¹, the return being through the running rail R³. The car circuits in ordinary running between stations are shown diagrammatically in Fig. 7, the course of the current being from C¹ through the brush B³, armature A¹, brush B⁶, channel C, journal J, and wheel W to the rail R³. In this diagram the field winding F¹ is shown connected in shunt with the armature through the rotary switches S⁹. In stations and places where the car is to run at reduced speed or be otherwise controlled, however, it is necessary that the field should be separately excited, in order that it may be kept at full strength while the voltage in the armature is reduced, or reversed relatively to the armature circuit. For this purpose I provide in such places an extra pair of conductor rails T¹, with corresponding collector shoes C² on the car. In ordinary running between stations the collector shoes C² are cut out of the field circuit and hang down as in Fig. 7. At the approaches to the stations, however, they come into contact with the sloping ends of the field conductor rails T¹ and are gradually raised to the position in which they appear in Figs. 8 to 10. At the same time, by means of mechanical connections between the collector shoes C² and the corresponding rotary switches S⁹, the latter are set in the position shown in Figs. 8 to 10. In this position it will be seen that the field of the motor is no longer connected in shunt with the armature, but to the two field conductor rails.

The details of construction of the rotary switches S⁹ are shown in Figs. 4 to 6. It will be seen that there are three contact segments S¹⁰, S¹¹ and S¹² mounted upon a slate insulating disk D. Two contact shoes C³ are pivoted at P⁷ upon opposite sides of the ring R⁴ and bear upon the segments. The ring R⁴ is insulated from the spindle S¹³ by which it is rotated through the pivots P⁶. The spring S¹⁴ presses the contact shoes against the contact segments. In one posi-

tion a connection is formed through the ring R^4 between the segment S^{12} and the segment S^{10} and in the other position between the segment S^{12} and the segment S^{11} .

5 The object of the pivoted mounting of the ring R^4 and shoes C^3 is to insure good electrical contact between them and the segments.

10 The rotary switches S^9 are rotated through the gears G^3 , G^4 , Figs. 1, 2 and 6, and shaft S^{15} by the pawl P^8 , which is depressed by the angle piece K attached to the slide S^{16} which carries at its lower extremity the collector shoe C^2 . The slide S^{16} is supported by the guide G^5 and the guide G^6 as 15 well as the rotary switch S^9 are mounted upon the wooden cross pieces Z . The spring S^{14} tends to keep the shoes in the position in which the pawl P^8 is raised, but when 20 the collector shoe C^2 is unsupported its weight together with that of the slide S^{16} depresses the pawl and sets the switch in the alternative position.

25 In Figs. 1 and 2 the parts are shown in the position they occupy when the collector shoe C^2 is supported upon its conductor rail T^1 .

30 In Fig. 8 the connections between the generator and the car are shown when the car is under control within a station and moving ahead at reduced speed. The main positive and negative leads from the generator are indicated at 1 and 40, respectively. C^6 is a controller having the contacts V^1 to V^8 , bridged as indicated. In this case the field circuit is from positive conductor 1 through V^1 , V^2 , the field circuit as heretofore described, V^7 and V^8 to negative conductor 40. The field is thus receiving the full voltage 35 of the generator. The armature circuit, however, is from positive conductor 1 through the resistance R^5 , V^3 , V^4 and the armature circuit as heretofore described to negative conductor 40. The reason for the 40 extra contact V^5 will be given later. The armature is thus receiving a voltage reduced by the fall of potential through the resistance R^5 , and the car consequently runs ahead at reduced speed.

45 In Fig. 9 are shown the connection where it is desired to brake the car and bring it to rest. Here the field connections are as in Fig. 8, but the armature instead of being connected to the generator is short circuited by 50 means of the bridge from V^4 to V^6 through the resistance R^6 . With the armature thus short-circuited if the field were not separately excited it would receive little or no current because of its high resistance compared with that of the armature circuit and the motor would be nearly inert. But with 55 the field separately excited to full strength the motor becomes a short-circuited generator requiring a very large couple to rotate its armature, and consequently acts as a

brake. The resistance R^6 is interposed in order to prevent an excessive current in the armature and also to regulate the distance within which the car is brought to rest.

60 Fig. 10 shows the connections for reversing the direction of motion of the car. They are the same as in Fig. 8 except that the field circuit is reversed, being from positive conductor 1 through V^1 , V^7 , the field circuit in the reverse direction, V^2 and V^8 to negative conductor 40.

65 Conductor cables may extend between the cars for the purpose of establishing a connection between the main conductor shoe C^1 of the first car and the motors of the following cars, the main conductor shoes of the latter being raised out of contact with the conductor rail T , in order that the changes in the current incident to controlling the train may affect all the motors simultaneously.

70 Fig. 11 is a diagram of the electrical connections between the generator, controllers and the various sections of a track passing through such a station as that just described in one direction, including the approach, the through and side tracks in the station and the adjacent outgoing sections. The track in the reverse direction, which has exactly 75 similar connections, is omitted for the sake of simplicity. The main conductor rail is electrically interrupted at E^3 , E^4 , E^5 , E^6 , J^5 , E^7 , E^8 , E^{10} and E^{11} , the intervening sections having electrical connections differing from one another, by which means the car is 80 controlled. The field conductor rails begin at E^2 and end at E^{12} . The car enters the region included within the diagram at E^1 at full speed, is retarded from E^3 to E^4 , still further retarded from E^4 to E^5 , brought 85 to rest at E^6 , passes from E^6 to J^5 at station speed, is accelerated from J^5 to and somewhat beyond E^{11} and passes E^{12} at full speed again. At E^1 the car is receiving the full 90 voltage of the generator and traveling at 95 full speed, the connections to and within it being as in Fig. 7, already described. The connections from the generator G^6 to this section are through 1, 2, 4, 11 and 12. The return circuit is through the running rails 100 R^3 and 13, 22, 34, 39, and 40 to the generator G^6 .

105 From E^2 to E^{12} the field of the motor is excited, always at full strength, through the field conductor rails, the connections within 110 the car being as in Figs. 8, 9 and 10, already described. The connection to the positive field conductor rail is through 1, 2, 4 and 15. The negative field conductor rail is connected through 14 and 13 to the running 115 rail, which forms a connection with the generator as above described.

120 From E^3 to E^4 the armature of the motor is in communication with the generator only through the resistance R^5 , which is so calcu- 130

lated that the car would normally be driven through it at station speed. So long as the speed of the car exceeds the station speed, therefore, no current will flow through the armature and the car will be retarded by friction and gravity until it reaches the station speed, at which it will continue to run. There is no braking of the car and the difference between its kinetic energy at full speed and at station speed is expended in useful work, which in a system of this kind I consider preferable to braking, for reasons that will be given later. The connection to the main conductor rail of this section is 15 through 1, 41, 47, 3, 5, and 16, the return circuit being as before.

The section from E^4 to E^6 is under the control of the controller C^5 and is normally short circuited as in the diagram, Fig. 11, 20 the portion from E^4 to E^5 being short circuited through the resistance R^6 and the remainder without resistance. The object in thus subdividing this section is that the car may be brought nearly but not quite to rest 25 in the first portion and then stopped with great positiveness in the short second portion in order that there may be as little variation in its stationary position as possible. The field conductor rails are electrically interrupted at E^4 and E^6 to permit of reversing the current in them for the purpose of reversing direction of motion of the car. The running rails R^3 are likewise electrically interrupted at these points for the reason 30 that when the motor armature is short circuited the current flows through it and consequently through the conductor and running rails in the reverse direction. The connection to the positive field conductor 35 rail of this section is through 1, 2, 4, V^1 , V^2 , and 17. The negative field conductor rail is connected through 21, V^7 , V^8 , 39 and 40. The connection which short circuits the motor armature is from the main conductor 40 rail T to the running rail R^3 through 18, V^4 , 9 the regulating resistance R^6 , 10, V^6 and 20, which will be found to agree with the connections in Fig. 9, already described. The short circuiting connection for the section 45 position is through 19, V^5 , 10, V^6 and 20, which is the same as before, excepting that it is through a different contact in the controller and the resistance R^6 is cut out.

When on the section between E^5 and E^6 50 the car is in plain view from the position of the controllers C^4 and C^5 , it carries on its forward end an indicator (not illustrated) which shows whether or not it is to be opened at the station. The attendant (by 55 means of a mechanism not shown) sets the track switch accordingly, *i. e.*, for the side track or through track, as the case may be, and then throws the controller C^5 into the position shown in Fig. 8, which, it will be 60 remembered, sends the car ahead at station

speed. In this diagram the conductors from both V^4 and V^5 are shown as connected to the main conductor rail T , but it must be understood that the former is connected on one side of E^5 and the latter on the other 70 side. By one movement of the controller, therefore, both portions of this section are given similar connections with the generator.

The car now enters upon the section E^6 to J^5 or through track, which, notwithstanding the cross-overs, is rendered electrically continuous by the connectors 23, 24 to 26 and 25 to 27. The side track is electrically interrupted at E^{15} and E^{16} , and the portions adjacent to the junctions S^{17} and J^5 are electrically connected to the through track by means of the connectors 28, 26 to 30 and 27 to 29; and 52, 53 to 55 and 54 to 56 respectively. The through track is permanently connected to the generator and the car once 85 on this section is no longer under control but continues to move at station speed until it passes off the section, either at E^{15} or at J^5 according as the track switch may have been set for the side track or through track. The 90 connection from G^6 to the positive field conductor rail of this section is through 1, 2 and 31. The negative field conductor rail is connected with the running rail through 33 and 34 as before. The connection to the main 95 conductor rail is through 1, 41, 47, 3 and 32. If the car has been directed onto the side track after passing E^{15} it comes under control of the controller C^4 which is similar to C^5 excepting that as this section is not subdivided the contact V^5 is unused. The connection from G^6 to the positive conductor rail of this section is through 1, 2, 6, V^1 , V^2 and 35. The negative conductor rail is connected to G^6 through 38, V^7 , V^8 , 39 and 40. 100 The short circuiting connection is from the main conductor rail at 36 through V^4 , 8, the regulating resistance R^6 , V^6 and 37. The field conductor and running rails are electrically interrupted at E^{15} and E^{16} for the 105 same reason as at E^4 and E^6 . After the car has been loaded or unloaded it is redespached by turning the controller in to the position shown in Fig. 8, as before. It is sometimes convenient to be able to reverse 110 the car when on this section and the section from E^4 to E^6 and send it back a few feet. For this purpose the controller position 115 shown in Fig. 10 and already described is provided. It will be observed that since the 120 cars always stop at the entrance to the station, they can never cross the junctions between main and side tracks except at the will of the operator and no complicated mechanism to prevent collision at these 125 points is necessary. After passing E^{16} the car is not under control again until it reaches the next station. Beyond J^5 the field conductor rails are electrically continuous until they end at E^{12} . The connection to the posi- 130

tive field conductor rail of this section is through 1, 41, 48 and 50. The negative field conductor rail is connected to the running rail as before at 51.

5 The car now passes over a series of sections at each of which portions of the resistance R^5 are successively cut out until at E^{11} the resistance is all cut out and it is receiving the full voltage of the generator again and shortly afterward is traveling at full speed. At E^{12} the field connections change back to those shown in Fig. 7.

10 The connection to the section of the main conductor rail between J^6 and E^7 is through 1, 41 to 46, and 49, the portion of the resistance R^5 between 46 and 47 having been cut out. Between E^7 and E^8 it is through 1, 41 to 45 and 57; and so on until beyond E^{11} it is through 1, 41, 48 and 61, the entire resistance having been cut out.

15 At the stations the tunnel, through which the cars may pass, is constructed as close to the surface as practicable. On each side of the station, however, it descends at a sharp 20 gradient, for about 300 feet, for example, the ordinary depth being from 25 to 30 feet. By this means the aid of gravity is secured both to accelerate the car when leaving and to retard it when approaching the 25 station. Moreover, in this way the kinetic energy of the car can generally be utilized to carry it up the approach to a station without undue loss of time, thus avoiding the waste of this energy which would result from stopping the car by braking. It is owing to this 30 feature and the separate excitation of the field at the stations that the use of shunt wound motors becomes practicable. The great advantage of using shunt rather than 35 series motors in a system of this kind is that they run practically at constant speed under a wide range of loads, consequently the cars will not race down the grades and lightly loaded cars will not overhaul heavily loaded 40 cars.

45 When direct current is employed for the motive power for the cars in my system as hereinbefore described, it is preferred that the motors on the respective cars shall be 50 shunt wound so that they shall be substantially constant speed motors, whereby the 55 separate or independent cars or trains running upon the same track shall maintain a substantially constant distance between each other and avoid collisions. In any 60 case, however, it is preferred that constant speed motors be employed. It is to be understood, however, that my invention is not limited to the employment of constant speed or shunt motors, except where specifically 65 specified in the claims, for it is apparent that many features of my system and invention are useful irrespective of the type of motor employed.

65 Where each car of a train is equipped

with driving motors the traveling contact shoes are employed on one car only, the connections being made to the other car through conductors as hereinbefore described, with the result that in a system employing control conductors near a station, as described, all the motors will be simultaneously and similarly affected and prevent jarring or 70 jolting between the cars of the train which would otherwise occur if the cars were to 75 come under the control of a station operator in succession.

What I claim is:

1. In an electric despatch system, track rails, a car movable thereon, an electric motor upon said car, supply conductors extending along said track rails for supplying current to said motor, motor field contact conductors extending along said track rails, the field of said motor being connected to 80 the motor armature when said car is beyond said motor field contact conductors, and automatic means operative when said car reaches said field contact conductors for disconnecting the motor field from the motor 85 armature and bringing the motor field into communication with said field contact conductors.

2. In an electric despatch system, a car, an electric motor thereon, motor field contact conductors extending part-way along the trackway near a station, independent armature contact conductors extending along the trackway, means on the car for disconnecting the motor field from the motor 90 armature, and a switch at a station for connecting said armature contact conductors together.

3. In an electric despatch system, a car, an electric motor thereon, rails on which said 105 car travels, motor armature and motor field contact conductors extending along the path of travel of said car and insulated from said rails, said motor field separately excited, and means at a station for short 110 circuiting the motor armature while the field is separately excited, whereby said car is braked.

4. In an electric despatch system, a car, an electric motor thereon, rails on which said 115 car travels, a source of energy, motor armature and motor field contact conductors extending along the path of travel of said car and insulated from said rails, said motor field being separately excited, and a controller at a station for disconnecting said armature from said source of energy and for short circuiting said armature while said motor field is separately excited, whereby said car is braked.

5. In an electric despatch system, a car, a motor thereon, main conductors, a discontinuous motor field conductor, a field conductor shoe engaging the same, switching mechanism operated by said field conductor 120

125

130

shoe when it comes into engagement with said field conductor, said switching mechanism when operated disconnecting the motor field from the main conductors and connecting it to the field conductor.

6. In an electric despatch system, a car, a motor thereon, rails on which said car travels, a source of energy, a field conductor energized at substantially constant voltage and extending along the path of travel of said car for separately exciting the motor field at substantially constant strength, a motor armature supply conductor extending along the path of travel of said car, said field and armature conductors insulated from said rails, an insulated section of said motor armature supply conductor connected to said source of energy through a resistance, said motor armature deriving current from said source of energy through said resistance, whereby the speed of the car is reduced as it reaches said section of said motor armature supply conductor.

7. In an electric despatch system, a car, a motor thereon, main conductors, a motor field contact conductor adjacent to a station only, and a controller at a station, the current supplied to said main and field conductors passing through said controller.

8. In an electric despatch system, a car, a motor thereon, main conductors, a motor field contact conductor adjacent to a station only, a controller at a station, said main and field conductors receiving current through said controller, and means in said controller for causing the motor field to be excited at full voltage and for causing a reduced voltage upon said main conductors.

9. In an electric despatch system, a car, a source of energy, a motor on said car, the line provided with a pair of main conductors and a field conductor, the motor field excited from said field conductor, a controller at a station, said main and field conductors receiving current through said controller, and means in said controller for causing full voltage to be impressed upon said motor field and for simultaneously disconnecting said main conductors from said source of energy and connecting them to each other.

10. In an electric despatch system, a car, a motor thereon, main contact conductors extending permanently along the trackway, a generator supplying current to said conductors, means at a station for disconnecting said main conductors from said generator and for connecting them to each other, and means for separately exciting the field of said motor while said main conductors are connected together.

11. In an electric despatch system, a car, a motor thereon, main contact conductors extending permanently along the trackway, a generator supplying current to said con-

ductors, a resistance, means at a station for disconnecting said main conductors from said generator and for connecting them to each other through said resistance, and means for separately exciting the field of 70 said motor while said main conductors are connected through said resistance.

12. In an electric despatch system, a car, a motor thereon, the line provided with a pair of main conductors, a controller at a 75 station, said main conductors receiving current through said controller, one of said conductors being subdivided, and means in said controller for connecting one part of said subdivided conductor to the other conductor through a resistance and simultaneously connecting another part of said conductor to the other main conductor without a resistance.

13. In an electric despatch system, a car, 85 an electric motor thereon, rails on which said car travels, a motor armature contact conductor insulated from said rails and extending along the path of travel of said car, means for dividing a running rail and said 90 contact conductor into sections, and conductors of different resistance values connected with said rail and conductor sections, said resistance conductors serving independently of each other as short-circuit 95 loads for said motor armature when said car reaches said sections, whereby said car is braked.

14. In an electric despatch system, a car, an electric motor thereon, rails on which 100 said car travels, a motor armature contact conductor insulated from said rails and extending along the path of travel of said car, means for dividing a running rail and said 105 contact conductor into sections, conductors of different resistance values connected with said rail and conductor sections, said resistance conductors serving independently of each other as short-circuit loads for said motor armature when said car reaches said 110 sections, whereby said car is braked, and means for separately exciting the motor field.

15. In an electric railway system, a car, a motor thereon for driving the same, independent armature and motor field contact conductors extending along the path of travel of said car, means dividing an armature contact conductor into sections, neighboring sections forming control and accelerating sections, a controller external to said car controlling said motor when said car is on said control section, and means for delivering current to said motor through said accelerating section independently of 120 125 said controller.

16. In an electric despatch system, a car, a motor thereon, main contact conductors divided into sections, a motor field contact conductor energized at substantially con- 130

stant voltage for separately exciting the motor field at substantially constant strength, and resistances permanently in the circuit of sections of said main conductors 5 adjacent to a station.

17. In an electric despatch system, a car, a motor thereon, main contact conductors divided into sections, a motor field contact conductor energized at substantially constant 10 voltage, and means permanently connected with said main conductor sections adjacent to a station for progressively changing the speed of a car, the field of said motor excited at substantially constant strength from said 15 motor field contact conductor.

18. In an electric despatch system, a car, a motor thereon, main contact conductors divided into sections, a motor field control conductor adjacent to a station, said field control 20 conductor energized at substantially constant voltage, and means permanently connected with said main conductor sections adjacent to a station for progressively changing the speed of a car, the field of said motor excited 25 at substantially constant strength from said motor field control conductor.

19. In an electric despatch system, a traveling car, an electric motor thereon for driving the same, rails on which said car travels, 30 motor armature and motor field contact conductors extending along the path of travel of said car, means for insulating said armature and field contact conductors from each other and from said rails, means dividing 35 the armature contact conductors into independent sections, conductors of different resistance values in circuit with said independent sections, and means for short circuiting said motor armature through said independent 40 sections while the motor field is separately excited.

20. In an electric despatch system, a traveling car, an electric motor thereon for driving the same, rails on which said car travels, 45 motor armature and motor field contact conductors extending along the path of travel of said car, means for insulating said armature and field contact conductors from each other and from said rails, means dividing 50 the armature contact conductors into independent sections, conductors of different resistance values in circuit with said independent sections, and a controller at a station for short circuiting the motor armature through 55 said independent sections while the motor field is separately excited.

21. In an electric despatch system, a traveling car, a motor thereon for driving the same, a source of energy, motor armature 60 and motor field contact conductors insulated from each other and extending along the path of travel of said car, said motor field contact conductor energized at substantially constant voltage, said motor armature con-

tact conductor divided into independent sections, and graduated resistances, said independent sections receiving current from said source of energy through said graduated resistances, said motor field separately excited at substantially constant strength from 70 a motor field contact conductor.

22. In an electric despatch system, a traveling car, a motor thereon for driving the same, main contact and motor field contact conductors extending permanently along the 75 trackway, and a controller at a station, the current supplied to said main and field conductors passing through different contacts of said controller.

23. In an electric despatch system, a traveling car, a motor thereon for driving the same, the line provided with main and motor field contact conductors, a controller at a station, said main and field contact conductors receiving current through said controller, and means in said controller for permitting the motor field to be excited at full voltage and for causing a reduced voltage 80 upon said main conductors.

24. In an electric despatch system, a station track, a through track leading past said station, a track switch for controlling traffic over either of said tracks, a traveling car, a motor thereon for driving the same, a track section immediately in front of said 90 switch, sectional contact conductors extending along said track section, a controller at said station coöperating with said contact conductors for bringing said car to rest in said track section, said controller in another 95 of its positions coöperating with said contact conductors for energizing said motor to move said car past said switch after said car has been brought to rest in said track section, and a second controller at said station 100 controlling said car after it has passed said switch.

25. In an electric despatch system, a car and an electric motor thereon for driving the same, a pair of adjacent contact conductors in communication with said motor for controlling the same, each of said contact conductors divided into several sections insulated from each other, means for short circuiting the armature of said motor 110 through the contact conductors of a section, and means for exciting the field of said motor at substantially full strength while said motor armature is short circuited.

26. In an electric despatch system, a pair 115 of adjacent contact conductors each divided into sections and insulated from each other, a traveling car deriving energy from said contact conductors, an electric motor on said car for driving the same, means for short 120 circuiting the armature of said motor through one or more sections of said pair of adjacent contact conductors, and means for

exciting the field of said motor at substantially full strength while said motor armature is short circuited.

27. In an electric despatch system, a traveling car, an electric motor thereon for driving the same, rails on which said car travels, a main contact conductor, motor field contact conductors insulated from said rails, said main and motor field conductors insulated from each other, and means for short circuiting the motor armature through said main contact conductors while the motor field is separately excited.

28. In an electric despatch system, the combination with a movable car, of a shunt wound motor upon said car for driving the same, contact conductors controlling the motor armature, contact conductors supplying energy for separately exciting the motor field, and means for short circuiting said motor armature through its contact conductors, said armature and field contact conductors insulated from each other.

29. In an electric despatch system, a station, running rails leading thereto, a car traveling over said rails, an electric motor on said car for driving the same, a motor supply contact conductor extending along said rails between stations and insulated from said rails, said contact conductor and a running rail divided into sections insulated from each other near said station, and a controller at said station for bringing said car to rest when said motor is in communication with the insulated sections of said rail and conductor near said station.

30. In an electric despatch system, the combination with a station and the trackway leading thereto, of a car movable over said trackway, an electric motor on said car for driving the same, a contact conductor extending along said trackway, a controller at said station, said controller in one position short circuiting the armature of said motor through said contact conductor for bringing said car to rest at said station, another contact conductor for separately exciting the field of said motor while its armature is short circuited, said controller having another position for delivering current to said motor for moving the car after having been brought to rest by motor braking, said contact conductors insulated from each other and from said trackway.

31. In an electric despatch system, the combination with a station and a trackway leading thereto, of a car adapted to move over said trackway, an electric motor on said car for driving the same, a sectioned motor armature contact conductor extending along said trackway, a motor field contact conductor extending along said trackway, a controller for electrically braking said motor through a section of said armature con-

tact conductor while the motor field is separately excited, a source of energy and a circuit controlled by said controller for putting said source of energy into communication with said armature and field contact conductors for moving said car after having been motor braked.

32. In a system of the character described, the combination with a car, of an electric motor thereon for driving the same, an armature contact conductor, switch mechanism on said car for disconnecting the motor field from the motor armature, a member disposed in the path of travel of said car for causing actuation of said switch mechanism when said car passes said member, motor field contact conductors, and a controller external to said car controlling the field of said motor through said field contact conductors.

33. In a system of the character described, the combination with a car, of an electric motor thereon for driving the same, switch mechanism on said car for disconnecting the motor field from the motor armature, a member on said car disconnected from but adapted to actuate said switch mechanism, and a second member disposed in the path of travel of said car and adapted to be engaged by said first mentioned member to actuate said switch mechanism.

34. In a system of the character described, the combination with a car, of an electric motor thereon for driving the same, rails on which said car travels, switch mechanism on said car for disconnecting the motor field from the motor armature, main contact conductors extending along the path of travel of said car for supplying current to said motor, and motor field contact conductors insulated from said rails and extending along a portion of the path of travel of said car, the motor field being brought into communication with said field contact conductors when said switch mechanism is actuated.

35. In a system of the character described, the combination with a car, of an electric motor thereon for driving the same, switch mechanism on said car for disconnecting the motor field from the motor armature, a motor field contact conductor extending along the path of travel of said car, a contact shoe carried by said car adapted to engage said conductor to actuate said switch mechanism and bring said motor field into communication with said motor field conductor.

36. In a system of the character described, the combination with a car, of an electric motor thereon for driving the same, rails on which said car travels, switch mechanism on said car for disconnecting the motor field from the motor armature, main supply con-

- ductors extending along the path of travel of said car, a motor field contact conductor insulated from said rails and extending along a portion of the path of travel of said car, and 5 a member near the end of said field contact conductor for actuating said switch mechanism to bring the motor armature into communication with said main conductors and the motor field into communication with said 10 field contact conductor.
37. In a system of the character described, a car, an electric motor thereon for driving the same, rails on which said car travels, main contact conductors extending 15 along the path of travel of said car for supplying energy to said motor, said conductors divided into insulated sections near a station, motor field contact conductors insulated from said rails near said station, said 20 motor field separately excited from said field contact conductors, means on said car for placing the motor field into communication with said field conductors and for placing the motor armature into communication with 25 said main conductors, and means for progressively changing the speed of said motor as said car passes over successive sections of said main conductors.
38. In an electric despatch system, a traveling car, a motor thereon for driving the 30 same, rails on which said car travels, motor armature and motor field contact conductors extending along the path of travel of said car and insulated from said rails, said motor 35 field separately excited, said armature contact conductors divided into independent sections, a controller at a station, and means in said controller for connecting said armature through a resistance associated with one 40 of said sections and when said car reaches another of said sections short circuiting said armature without a resistance, said motor field separately excited while said motor armature is in communication with said 45 independent sections.
39. In a system of the character described, a car, an electric motor thereon for driving the same, main contact conductors extending along the path of travel of said car for supplying energy to said motor, said conductors 50 divided into insulated sections near a station, motor field contact conductors near said station, means on said car for placing the motor field into communication with 55 said field conductors and for placing the motor armature into communication with said main conductors, means for progressively changing the speed of said motor as said car passes over successive sections of 60 said main conductors, said field contact conductors each being divided into sections near said station, said sections of said conductors insulated from each other, and a switch at 65 said station for reversing the current in said field contact conductors.

40. In a system of the character described, a car, a motor thereon for driving the same, main contact conductors divided into sections and extending along the trackway for delivering energy to said motor, a motor 70 field contact conductor energized at substantially constant voltage for separately exciting the motor field at substantially constant strength, means connected with the sections of said main contact conductor whereby said sections serve to impress different voltages upon the motor armature, the motors on the different cars or trains passing over said main contact sections being constant speed motors, whereby the cars or trains maintain 75 their spacing.

41. In a system of the character described, a car, a motor thereon for driving the same, main contact conductors extending along the path of travel of said car for supplying energy to said motor, armature and field contact conductors intervening between said main contact conductors and a station, means for connecting the armature terminals and the field terminals to said armature and field contact conductors respectively when said car reaches said armature and field contact conductors, and a controller at a station controlling said armature through said 80 armature and field contact conductors.

42. In a system of the character described, a car, a motor thereon for driving the same, rails on which said car travels, main contact conductors extending along the path of travel of said car for supplying energy to said motor, armature and field contact conductors insulated from said rails intervening between said main contact conductors and a station, means for connecting the armature terminals and the field terminals to said armature and field conductors respectively when said car reaches said armature and field conductors, and a controller at said 100 station for motor braking said car.

43. In a system of the character described, a car, a motor thereon for driving the same, rails on which said car travels, main contact conductors extending along the path of travel of said car for supplying energy to said motor, armature and field contact conductors insulated from said rails intervening between said main contact conductors and a station, means for connecting the armature terminals and the field terminals to said armature and field conductors respectively when said car reaches said armature and field conductors, and a controller for short 115 circuiting said armature.

44. In a system of the character described, a car, a motor thereon for driving the same, main contact conductors extending along the path of travel of said car for supplying energy to said motor, armature and field contact conductors intervening between said main contact conductors and a station, 120

125

means for connecting the armature terminals and the field terminals to said armature and field contact conductors respectively when said car reaches said armature and field contact conductors, and a controller at 5 said station in successive positions short circuiting said armature through progressively smaller resistances.

45. In a system of the character described, 10 a car, a motor thereon for driving the same, rails on which said car travels, main contact conductors extending along the path of travel of said car for supplying energy to said motor, armature and field contact conductors insulated from said rails intervening 15 between said main contact conductors and a station, means for connecting the armature terminals and the field terminals to said armature and field contact conductors 20 respectively when said car reaches said armature and field contact conductors, and a controller at said station for progressively reducing the voltage upon said armature.

46. In a system of the character described, 25 a car, a motor thereon for driving the same, rails on which said car travels, main contact conductors extending along the path of travel of said car for supplying energy to said motor, armature and field contact conductors insulated from said rails intervening 30 between said main contact conductors and a station, means for connecting the armature terminals and the field terminals to said armature and field contact conductors 35 respectively when said car reaches said armature and field contact conductors, and a controller at said station for progressively reducing the voltage impressed upon said armature, and short circuiting said armature. 40

47. In a system of the character described, a car, a motor thereon for driving the same, main contact conductors extending along the path of travel of said car for supplying 45 energy to said motor, armature and field contact conductors intervening between said main contact conductors and a station, means for connecting the armature terminals and the field terminals to said armature and field contact conductors respectively 50 when said car reaches said armature and field contact conductors, and a controller at said station for progressively reducing the voltage upon said armature, short circuiting 55 said armature, and admitting current to said armature for restarting said motor.

48. In a system of the character described, a car, a motor thereon for driving the same, main contact conductors extending along the path of travel of said car for supplying energy to said motor, armature and field contact conductors intervening between said main contact conductors and a station, means for connecting the armature terminals and the field terminals to said armature 60

and field contact conductors respectively when said car reaches said armature and field contact conductors, the path of travel of said car being branched at a station into station and other branches, a track switch 70 controlling said branches, and control mechanism at a station for bringing said car to rest before reaching said switch, and for thereafter energizing said motor to move said car to any of said branches. 75

49. In a system of the character described, a car, a motor thereon for driving the same, main contact conductors extending along the path of travel of said car for supplying energy to said motor, armature and field contact conductors intervening between said main contact conductors and a station, means for connecting the armature terminals and the field terminals to said armature and field contact conductors respectively 80 when said car reaches said armature and field contact conductors, the path of travel of said car being branched at a station into station and other branches, a track switch 85 controlling said branches, and control mechanism at a station for bringing said car to rest before reaching said switch, for thereafter energizing said motor to move said car to any of said branches, and for thereafter energizing said motor to move said car 90 from any of said branches to the path of travel of said car beyond said station. 95

50. In a system of the character described, a car, a motor thereon for driving the same, main contact conductors divided into sections 100 and extending along the trackway for delivering energy to said motor, a motor field contact conductor energized at substantially constant voltage for separately exciting the motor field at substantially constant 105 strength, means connected with said sections of said main contact conductor whereby said sections serve to impress different voltages upon the motor armature, the motors on the different cars or trains after passing over 110 said main contact sections becoming shunt motors, whereby the cars or trains maintain their spacing.

51. In a system of the character described, a car, a direct current shunt motor thereon 115 for driving the same, main contact conductors extending along the path of travel of said car for supplying energy to said motor, armature and field contact conductors intervening between said main contact conductors and a station, means for connecting the armature terminals and the shunt field terminals to said armature and field contact conductors respectively when said car reaches said armature and field contact conductors, and a controller at a station controlling 120 said motor through said armature and field contact conductors. 125

52. In a system of the character described, a car, a motor thereon for driving the same, 130

rails on which said car travels, main contact conductors extending along the path of travel of said car for supplying energy to said motor, armature and field contact conductors insulated from said rails and displacing said main contact conductors along a portion of the travel of said car, and switching mechanism on said car for connecting the motor armature and field to said armature and field contact conductors respectively.

53. In a system of the character described, a car, a motor thereon for driving the same, rails on which said car travels, main contact conductors extending along the path of travel of said car for supplying energy to said motor, armature and field contact conductors insulated from said rails and displacing said main contact conductors along a portion of the travel of said car, and automatic switching mechanism on said car for connecting the motor armature and field to said armature and field contact conductors respectively when said car reaches said armature and field contact conductors.

54. In a system of the character described, a car, a motor thereon for driving the same, main contact conductors extending along the path of travel of said car for supplying energy to said motor, armature and field contact conductors displacing said main contact conductors along a portion of the travel of said car, switching mechanism on said car for connecting the motor armature and field to said armature and field contact conductors respectively, and a controller at a station controlling said motor through said armature and field contact conductors.

55. In a system of the character described, a car, a motor thereon for driving the same, rails on which said car travels, main contact conductors extending along the path of travel of said car for supplying energy to said motor, armature and field contact conductors insulated from said rails and displacing said main contact conductors along a portion of the travel of said car, switching mechanism on said car for connecting the motor armature and field to said armature and field contact conductors respectively, and a controller at a station controlling the motor armature through said armature contact conductors.

56. In a system of the character described, a car, a motor thereon for driving the same, main contact conductors extending along the path of travel of said car for supplying energy to said motor, armature and field contact conductors displacing said main contact conductors along a portion of the travel of said car, switching mechanism on said car for connecting the motor armature and field to said armature and field contact conductors respectively, and a controller at a

station controlling said motor field through 65 said field contact conductors.

57. In a system of the character described, a car, a motor thereon for driving the same, main contact conductors extending along the path of travel of said car for supplying energy to said motor, armature and field contact conductors displacing said main contact conductors along a portion of the travel of said car, automatic switching mechanism on said car for connecting the motor armature and field to said armature and field contact conductors respectively when said car reaches said armature and field contact conductors, and a controller at a station controlling said motor through said armature and field contact conductors.

58. In a system of the character described, a car, rails on which said car travels, a motor on said car for driving the same, motor armature and field contact conductors extending along the path of travel of said car independently of said rails and adapted to communicate with said motor, a controller at a station, automatic means for transferring said motor to the control of said station controller when said car reaches a pre-determined point, said controller short circuiting the motor armature while the motor field is separately excited from the motor field contact conductor.

59. In an electric despatch system, a traveling car, a motor thereon for driving the same, rails on which said car travels, motor armature and motor field contact conductors extending along the path of travel of said car and insulated from said rails, said armature conductors divided into independent sections including conductors of different resistance values, and means for short circuiting the motor armature through said sections while the motor field is separately excited.

60. In an electric despatch system, a traveling car, a motor thereon for driving the same, rails on which said car travels, motor armature and motor field contact conductors extending along the path of travel of said car and insulated from said rails, said armature conductors divided into independent sections including conductors of different resistance values, and a controller at a station for short circuiting said motor armature through said independent sections while said motor field is separately excited.

61. In an electric despatch system, a traveling car, a motor thereon for driving the same, a motor armature and two motor field contact conductors extending along the path of travel of said car, such field contact conductors energized at substantially constant voltage, said motor field separately excited at substantially constant strength from a motor field contact conductor, said motor

5 armature contact conductors divided into a plurality of independent sections adjacent to a station, and means for impressing voltages of different magnitudes upon said independent sections, whereby different voltages are impressed upon said motor armature as said car proceeds.

62. In an electric despatch system, a traveling car, an electric motor on said car for 10 driving the same, rails on which said car travels, a contact conductor extending permanently along the trackway and delivering energy to said motor, said contact conductor having an independent section, and means 15 for short circuiting the armature of said motor through said independent section of contact conductor, and means insulated from said rails for separately exciting the field of said motor while its armature is short 20 circuited.

63. In an electric despatch system, a traveling car, an electric motor thereon for driving the same, rails on which said car travels, motor armature and motor field contact conductors insulated from each other and said rails, and means for short circuiting said motor armature through a motor armature contact conductor while said motor field is separately excited.

64. In an electric despatch system, a traveling car, a motor thereon for driving the same, rails on which said car travels, motor armature and motor field contact conductors insulated from each other and said rails, and extending permanently along the trackway, and means for short circuiting said motor armature through a motor armature contact conductor while said motor field is separately excited.

65. In an electric despatch system, a traveling car, a motor thereon, motor armature and motor field contact conductors insulated from each other and extending along the path of travel of said car, said motor field 45 separately excited from the motor field contact conductor, said armature contact conductor divided into a plurality of sections insulated from each other, means for impressing normal voltage upon a section of said armature contact conductor, means impressing less voltage upon a succeeding section of armature contact conductor for reducing the motor speed, means associated with another of said sections for electro- 50 dynamically braking said motor, a controller associated with said last named section for reenergizing said motor, and succeeding sections of said armature contact conductor sections having progressively increasing voltages impressed thereon for automatically accelerating said motor.

66. In an electric despatch system, the combination with a car, of a motor thereon for driving the same, a motor armature contact conductor divided into sections extend-

ing along the path of travel of said car, a source of current means permanently electrically connected with a section of armature contact conductor and said source of current for reducing the speed of said motor as said 70 car arrives on said section, and a controller external to said car controlling a succeeding section of said armature contact conductor for establishing an armature circuit independently of said source of energy for braking said motor.

67. In an electric despatch system, the combination with through and side tracks, of a car adapted to move thereover, a motor on said car for driving the same, motor armature contact conductors divided into sections extending along said through and side tracks, means permanently electrically connected with sections of said motor armature conductors for reducing the speed of 85 said motor as said car approaches the junction of said through and side tracks, a controller at a station controlling other sections of motor armature contact conductors for braking said motor, and a circuit controlled 90 by said controller for again energizing said motor to advance said car past said junction between said through and side tracks.

68. In an electric despatch system, the combination with through and side tracks, 95 of a car adapted to move thereover, a motor on said car for driving the same, motor armature contact conductors divided into sections extending along said through and side tracks, means permanently electrically connected with sections of said motor armature conductors for reducing the speed of said motor as said car approaches the junction of said through and side tracks, a controller 100 at a station controlling other sections of motor armature contact conductors for braking said motor, and a second controller at said station controlling said motor armature contact conductor associated with said side track.

69. In an electric despatch system, the combination with through and side tracks, of a car adapted to move thereover, a motor on said car for driving the same, motor armature contact conductors divided into sections extending along said through and side tracks, means permanently electrically connected with sections of said motor armature conductors for reducing the speed of said motor as said car approaches the junction of 115 said through and side tracks, a controller at a station controlling other sections of motor armature contact conductors for braking said motor, a circuit controlled by said controller for again energizing said motor to 120 advance said car past said junction between said through and side tracks, and a second controller at said station controlling said motor armature contact conductor associated with said side track.

70 130

70. In an electric railway system, a car, an electric motor thereon, running rails for said car, motor armature and motor field contact conductors extending along the path of travel of said car and insulated from each other and from said running rails, the field of said motor separately excited through a motor field contact conductor, and means external to said car for closing the circuit of 5 said armature of said motor while said field is separately excited, whereby said car is braked.

71. In an electric railway system, a car, an electric motor thereon, running rails for 15 said car, motor armature and motor field contact conductors extending along the path of travel of said car and insulated from each other and from said running rails, the field of said motor excited from a motor field 20 contact conductor, one terminal of the armature of said motor connected with said running rails and the other terminal of said armature connected with a motor armature contact conductor, and switching means external to 25 said car for bringing said motor armature into a braking circuit including said running rails and said armature contact conductor, whereby said car is braked.

72. In an electric railway system, a car, 30 running rails therefor, an electric motor thereon, a motor armature contact conductor extending along the path of travel of said car, means dividing said armature contact conductor and a running rail into sections, 35 and braking circuits of different resistances having branches connected to different sections of said rail and armature contact conductors.

73. In an electric railway system, a car, 40 running rails therefor, an electric motor thereon, a motor armature contact conductor extending along the path of travel of said car, means dividing said armature contact conductor and a running rail into sections, 45 and braking circuits of different resistances having branches connected to different sections of said rail and armature contact conductor, and means for separately exciting the motor field.

74. In an electric railway system, a car, 50 an electric motor thereon, running rails for said car, motor armature and motor field contact conductors extending along the path of travel of said car and insulated from each 55 other and from said running rails, the motor field excited from a motor field contact conductor, means dividing an armature contact conductor into sections, a terminal of said armature connected with said running rails 60 and the other terminal of said armature connected in succession with said sections of armature contact conductor, and conductors of different resistance values having a common terminal in said running rails and

their other terminals in said sections of armature contact conductor.

75. In an electric railway system, a car, an electric motor thereon, running rails for 70 said car, motor armature and motor field contact conductors extending along the path of travel of said car and insulated from each other and from said running rails, the motor field excited from a motor field contact conductor, means dividing an armature contact conductor into sections, a terminal of said 75 armature connected with said running rails and the other terminal of said armature connected in succession with said sections of armature contact conductor, conductors of different resistance values having a common 80 terminal in said running rails and their other terminals in said sections of armature contact conductor, and means external to said car controlling the closure of circuit of said armature through said conductors while 85 said motor field is excited.

76. In an electric railway system, a traveling car, a motor thereon, armature and field contact conductors extending along the path of travel of said car, an armature contact conductor divided into sections, a braking resistance connected to one of said sections, and means external to said car for reversing said motor through said contact conductors and for braking said motor through 95 said resistance.

77. In an electric railway system, a car, a motor thereon, armature and field contact conductors extending along the path of travel of said car, an armature contact conductor divided into sections, an armature braking circuit including one of said sections, and a controller external to said car for reversing the field of said motor and closing said braking circuit.

78. In an electric railway system, a car, a motor thereon, armature and field contact conductors extending along the path of travel of said car, and a controller external to said car, said controller in different positions braking and reversing said motor.

79. In an electric railway system, a car, a motor thereon, rails on which said car travels, armature and field contact conductors insulated from said rails and extending along the path of travel of said car, and a controller external to said car, said controller in different positions starting and braking said car.

80. In an electric railway system, a car, a 120 motor thereon, armature and field contact conductors extending along the path of travel of said car, and a controller external to said car, said controller in different positions starting, reversing and braking said 125 motor.

81. In an electric railway system, the combination with main and side tracks, of a

car adapted to move thereover, a motor on said car for driving the same; motor armature and field contact conductors insulated from and extending along said main and side tracks, a motor armature contact conductor divided into sections, a section of said armature contact conductor in advance of the junction of said main and side tracks, and a controller external to said car for electro-dynamically braking said motor in advance of said junction.

82. In an electric railway system, the combination with main and side tracks, of a car adapted to move thereover, a motor on said car for driving the same, motor armature and field contact conductors extending along said main and side tracks, a motor armature contact conductor divided into sections, a section of said armature contact conductor in advance of the junction of said main and side tracks, and a controller external to said car for braking said motor in advance of said junction, said controller having another position for re-starting said car to move the same past said junction.

83. In an electric railway system, the combination with main and side tracks, of a car adapted to move thereover, a motor on said car for driving the same, motor armature and field contact conductors extending along said main and side tracks, a motor armature contact conductor divided into sections, a section of said armature contact conductor in advance of the junction of said main and side tracks, a controller external to said car for braking said motor in advance of said junction, said controller having another position for moving said car over said junction to said side track, and a second controller external to said car for controlling the same through said contact conductors while on said side track.

84. In an electric railway system, the combination with main and side tracks, of a car adapted to move thereover, a motor on said car for driving the same, motor armature and field contact conductors extending along said main and side tracks, a motor armature contact conductor divided into sections, a section of said armature contact conductor in advance of the junction of said main and side tracks, a controller external to said car for braking said motor in advance of said junction, said controller having another position for moving said car over said junction to said side track, and a second controller external to said car for controlling the same through said contact conductors while on said side track, said second controller having different positions for starting and reversing said car.

85. In an electric railway system, the combination with main and side tracks, of a car adapted to move thereover, a motor on said car for driving the same, motor armature and field contact conductors insulated from and extending along said main and side tracks, a motor armature contact conductor divided into sections, a section of said armature contact conductor in advance of the junction of said main and side tracks, and a controller external to said car for braking said motor in advance of said junction, said controller having another position for moving said car over said junction to said side track, and a second controller external to said car for controlling the same through said contact conductors while on said side track, said second controller having different positions for starting and reversing said car.

ture and field contact conductors extending along said main and side tracks, a motor armature contact conductor divided into sections, a section of said armature contact conductor in advance of the junction of said main and side tracks, a controller external to said car for braking said motor in advance of said junction, said controller having another position for moving said car over said junction to said side track, and a second controller external to said car for controlling the same through said contact conductors while on said side track, said second controller having different positions for starting and braking said car.

86. In an electric railway system, the combination with main and side tracks, of a car adapted to move thereover, a motor on said car for driving the same, motor armature and field contact conductors extending along said main and side tracks, a motor armature contact conductor divided into sections, a section of said armature contact conductor in advance of the junction of said main and side tracks, a controller external to said car for braking said motor in advance of said junction, said controller having another position for moving said car over said junction to said side track, and a second controller external to said car for controlling the same through said contact conductors while on said side track, said second controller having different positions for starting and braking said car.

87. In an electric railway system, the combination with main and side tracks, of a car adapted to move thereover, a motor on said car for driving the same, motor armature and field contact conductors extending along said main and side tracks, a motor armature contact conductor divided into sections, a section of said armature contact conductor in advance of the junction of said main and side tracks, a controller external to said car for braking said motor in advance of said junction, said controller having another position for moving said car over said junction to said side track, and a second controller external to said car for controlling the same through said contact conductors while on said side track.

88. In an electric railway system, a car, a motor thereon, motor armature and field contact conductors extending along the path of travel of said car, a source of current, a resistance, and a controller external to said car for reversing said motor and simultaneously bringing said resistance into circuit with the armature of said motor and said source of current.

89. In an electric railway system, a car, a motor thereon, rails on which said car travels, motor armature and field contact conductors insulated from said rails extending along the path of travel of said car, resist-

ance and a controller external to said car, said controller in one position bringing resistance into the circuit of said armature for starting the same and in another position bringing resistance into the circuit of said armature for braking the same.

- 5 90. In an electric railway system, a car, a motor thereon, rails on which said car travels, motor armature and motor field contact conductors insulated from said rails extending along the path of travel of said car, and resistances and a controller external to said car, a source of current, said controller in one position bringing one of said resistances 10 and said source of current into the circuit of said armature for starting the same, and in another position bringing another of said resistances into the circuit of said armature for braking the same.
- 15 91. In an electric railway system, a car, a motor thereon, motor armature and motor field contact conductors extending along the path of travel of said car, and resistances and a controller external to said car, said controller in one position reversing said motor 20 and bringing one of said resistances into the circuit of said armature, and in another position bringing another of said resistances into the circuit of said armature for braking the same.

- 25 92. In an electric railway system, a car, a motor thereon, rails on which said car travels, motor armature and field contact conductors insulated from said rails extending along the path of travel of said car, a source of energy, and a controller external to said car for dis-connecting said source of 30 to said car for dis-connecting said source of

current from said armature and bringing said armature into a braking circuit.

93. In an electric railway system, a car, a motor thereon, motor armature and field contact conductors extending along the path of travel of said car, a source of energy, and a controller external to said car for dis-connecting said source of current from said armature and bringing said armature into a braking circuit, an armature contact conductor divided into sections, whereby said controller in different positions gives to said armature braking circuit different resist- 40 45 50 ances.

94. In an electric railway system, a car, a motor thereon for driving the same having an armature and a field winding, independent contact conductors extending along the trackway and communicating respectively with said armature and field winding, means dividing said contact conductors into sections, neighboring lengths of said contact conductors at a station forming a station 60 section and a succeeding accelerating section, a controller controlling said car through the sectional contact conductors of said station section, and means associated with said contact conductors of said accelerating section for moving said car forward beyond said station independently of said controller.

In testimony whereof I have hereunto affixed my signature in the presence of the two subscribing witnesses.

KENNETH E. STUART.

ANNA E. STEINBOCK.

Copies of this patent may be obtained for five cents each, by addressing the "Commissioner of Patents, Washington, D. C."

It is hereby certified that in Letters Patent No. 1,150,902, granted August 24, 1915, upon the application of Kenneth E. Stuart, of Philadelphia, Pennsylvania, for an improvement in "Systems of Electric Despatch," errors appear in the printed specification requiring correction as follows: Page 2, line 50, for the word "connection" read *connections*; page 4, line 27, after the word "feet" strike out the period and insert a comma and the words *for example.*; page 8, line 94, claim 41, after the word "armature," insert the words *and field*; page 12, lines 37-38, claim 72, for the word "conductors" read *conductor*; and that the said Letters Patent should be read with these corrections therein that the same may conform to the record of the case in the Patent Office.

Signed and sealed this 21st day of September, A. D., 1915.

[SEAL.]

J. T. NEWTON,

Acting Commissioner of Patents.
